UNITED STATES PATENT OFFICE.

FERDINAND FIECHTL, OF CHERRYVALE, KANSAS, AND WILLIAM KAPPELMANN, OF ST. FRANCOIS, MISSOURI.

VERTICAL-RETORT SMELTING FURNACE.

Application filed February 18, 1924. Serial No. 693,663.

To all whom it may concern:

Be it known that we, FERDINAND FIECHTL and WILLIAM KAPPELMANN, citizens of the United States and Germany, respectively, 5 residing at Cherryvale and St. Francois, respectively, in the counties of Montgomery and St. Francois, respectively, and States of Kansas and Missouri, respectively, have invented new and useful Improvements in 10 Vertical-Retort Smelting Furnaces, of which the following is a specification.

This invention relates to improvements in smelting furnaces of the vertical retort type, particularly adapted for the reduction 15 of zinc.

An object of the invention resides in the provision of a smelting furnace which includes a double tier of superimposed retorts which increases the capacity of the furnace 20 in addition to working off the charge more thoroughly.

Another object of the invention is the provision of novel means for sealing the bottom of the retorts and for providing these 25 bottoms with flared or bell-shaped ends.

Another object of the invention resides in the novel arrangement of the retorts, whereby the zinc vapors are directed into a common filtering chamber and from there 30 into condensers, means being provided whereby one or more of the retorts may be eliminated when desired.

Another object of the invention resides in the provision of convenient means for cleaning 35 the retorts without removing the condensers and in means whereby the bottoms of the retorts may be opened and closed simultaneously or individually as desired.

Another object of the invention is the 40 provision of means included in the sealing means for the bottoms of the retorts for keeping the said bottoms cool.

Another object of the invention resides in forming the charge into briquetted cylindrical form having an opening in the center, which opening provides the double advantage of forming a passage for the vapors and for more readily working off the charge due to the hollow formation of the briquet. 45

A further object is the provision of novel 50 means for removing the residue or exhausted charge from the ash hoppers of the furnace and for providing means for the removal of slag formations and for inspection of the interior of the furnace.

With the above and other objects in view, the invention further includes the following novel features and details of construction, to be hereinafter more fully described, illustrated in the accompanying drawings and 60 pointed out in the appended claims.

In the drawings:

Figure 1 is a view partly in front elevation and partly in section illustrating a portion of a smelting furnace constructed in 65 accordance with the invention.

Figure 2 is a vertical sectional view taken at right angles to Figure 1.

Figure 3 is a section on the line 3—3 of 70 Figure 1.

Figure 4 is an enlarged fragmentary sectional view showing the manner of sealing the bottoms of the retorts.

Figure 5 is a section on the line 5—5 of 75 Figure 2.

Figure 6 is an enlarged fragmentary view of the air cylinder and its operating connections.

Figure 7 is an enlarged fragmentary sectional view of the connection between one 80 of the retort bottom controlling arms and its shaft.

Figure 8 is an enlarged fragmentary sectional view illustrating the means whereby 85 the retort closures may be controlled.

Referring to the drawings in detail wherein like characters of reference denote corresponding parts, the improved furnace as shown comprises walls 10 which are provided with an inner lining 11 of fire brick 90 and an intermediate layer 12 of insulating brick, a bottom 13, a top wall or arch 14 and intermediate arches 15, the last named arches being supported upon the lining 11 and partitions 16.

This construction forms a housing or casting for a plurality of retorts, the latter including upper and lower sections 17 and 18 respectively, the sections communicating and being arranged in superposed relation 100 so as to provide increased capacity and to permit of a thorough working-off of the charge. The retorts further include a top section 19 which is provided with an opening 20. These openings communicate with a filter chamber 21 which surrounds the top section of the retorts so that the zinc vapor will pass from the retorts through the openings 20 into the filtering chamber and from this chamber to condensers 22, from 110

where the zinc is drawn off in liquid form, as well be readily understood by those familiar with the art. The upper ends of the retorts are provided with openings 23 which are designed to receive tapered plugs or closures 24, the latter being of suitable fire-proof material and having a snug fit within the openings 23. The arches 16 are provided with openings for the passage of 10 the retorts, the said openings being of relatively large diameter, while the retorts are spaced from the walls of the opening by means of lugs 25 so as to provide for the passage of gases and permit the said gases 15 to circulate freely about the retorts. The retorts are slightly tapered for the purpose of reducing friction between the retort and the charge.

The charge is supplied to the retort preferably in the form of circular briquets 26 having openings 27 extending therethrough. These briquets are preferably mounted upon cars or trucks 28 which operate over rails 29 mounted upon the furnace. The briquets 25 may be inserted within the retorts by means of rods passed through the openings 27, the said briquets being lowered into position and the rods withdrawn, while the residue will be disposed of in a manner hereinafter 30 described. The walls 10 are provided with openings 28 through which access may be had to the interior of the furnace, the openings being normally closed by tiles 29.

The lower ends of the retorts communicate with flared openings 30 provided in the bottom 13 of the furnace and these openings are closed by valves or closures 31, each of which engages a plate 32 located at the bottom of the flared openings 30. This 35 plate is provided with upper and lower seats 33 and 34 respectively which are engaged by the valve 31 to close the bottom of the retorts. The upper seat 33 when engaged by the valve 31 acts to prevent the escape of 40 the charge, while the valve is surrounded between the upper and lower seat with a water or other liquid seal arranged within a chamber 35, the latter being formed between the valve and the plate 32. Liquid 45 is supplied to this chamber through a suitable supply pipe 36 and a passage 37, the said water or liquid passing out through an L-shaped passage 38, the upper or discharge end of which regulates the amount of 50 water within the chamber 35.

The valves are rotatably supported upon rods 37, the latter being movable through spiders or guides 38. The rods 37 are adapted to be engaged by arms or levers 39 55 secured to shafts 40, the securing means being in the form of pins 41. The shafts 40 extend through the furnace and carry arms 39 for controlling a row or series of retorts so that the valves 31 of a row or series may 60 be simultaneously operated. By removing

any of the pins 41 the particular valve of any of the retorts will be free from operation by its shaft 40 and the valve may be held in closed position by means of a dog 42 which engages the arm or lever 39 of the valve disconnected. The pin 41 is of a determined shearing strength and should the rocking movement of the shaft 40 for any reason be excessive, the pin will be sheared off so that no other damage will be effected. 70

The shaft 40 has secured thereto a lever or arm 43. This lever or arm 43 carries a pin 44 which is adapted for engagement with a slot provided in a bar 45, the engagement of the pin within this slot being controlled by a handle or lever 46. The bar 45 is connected to the piston rod of an air cylinder 47 which is controlled by a valve 48. This valve has secured thereto an arm 49 having an operating rod 50 connected thereto to provide controlling means for the air cylinder, whereby the valves 31 of a row of retorts may be simultaneously controlled and the exhausted charge discharged from the retorts. As before stated, any particular retort may be cut out by disconnecting the arm or lever 39 from the shaft 40, while the retort so cut out is adapted to have its opening 20 closed by a tile 51, as illustrated in Figure 3 of the drawings. 85

The exhausted charges from the retorts are directed into hoppers 52 from where they pass into conveyor pipes 53, the residue being forced through these pipes by air from nozzles 54. These nozzles are carried by branch pipes which extend from a common supply pipe 55 and each nozzle is controlled by a valve 56. 90

The furnace is adapted to utilize different fuels, such as natural gas, producer gas and pulverized coal, the fuel being fed to the furnace through pipes 57 having burners 58 extending therefrom the latter being arranged in vertical rows and controlled by valves 59. 100

The furnace is fired from one end, the gases rising to the top, while a uniform heat is provided throughout the combustion chambers of the furnace through the arrangement of the burners 58. 110

The invention is susceptible of various changes in its form, proportions and minor details of construction and the right is herein reserved to make such changes as properly fall within the scope of the appended claims. 115

Having described the invention what is claimed is:—

1. In a smelting furnace, vertical retorts of sectional formation, one section being disposed above and forming a continuation of the other section and means for supporting said sections, said means including a horizontally disposed arch having openings therein of larger diameter than the outside 125

diameter of the retorts and spacing elements between the retorts and walls of the openings to provide passages.

2. In a smelting furnace, vertically disposed retorts, valves for closing the bottoms of the retorts, means for operating the valves and a combined sealing and cooling means for the valves.

3. In a smelting furnace, vertically disposed retorts, a movable bottom for each of the retorts, said bottom including spaced valve faces, spaced seats at the lower end of each of the retorts for engagement by said faces and a liquid sealing agent for the lower face and seat.

4. In a smelting furnace, vertically dis-

posed retorts, a movable bottom for each of the retorts, said bottom including spaced valve faces, spaced seats at the lower end of each of the retorts for engagement by said faces and a combined cooling and sealing agent surrounding the movable bottom between the seats.

5. In a charge for smelting furnaces, a briquette having an opening therein to provide a passage and to facilitate handling of the charge.

In testimony whereof we affix our signatures.

FERDINAND FIECHTL.
WILLIAM KAPPELMANN.
